UNITED STATES PATENT OFFICE.

CLAUDE L. POST, OF CHICAGO, ILLINOIS.

SHAPER FOR PRINTING PLATES OR THE LIKE.

Application filed April 3, 1922. Serial No. 549,246.

To all whom it may concern:

Be it known that I, CLAUDE L. Post, a citizen of the United States, residing at Chicago, in the county of Cook and State 5 of Illinois, have invented certain new and useful Improvements in a Shaper for Printing Plates or the like, of which the following is a description.

My invention relates to improvements in 10 a shaper or former for printing plates or the like, and more especially to means for shaping or "setting" an electrotype, printing plate, etching plate, or the like so that its shape will conform to the shape of the 15 printing roll or the like upon which said plate is to be mounted for its printing operation. The invention has among its other objects the production of a device of the kind described that is simple, convenient, 20 compact, durable, reliable, efficient and satisfactory for use wherever found applicable. Many other objects and advantages of the construction herein shown and described will be obvious to those skilled in the art 25 from the disclosure herein given.

To this end, my invention consists in the novel construction, arrangement and combination of parts herein shown and described, and more particularly pointed out in the 30 claims.

In the drawings, wherein like reference characters indicate like or corresponding parts,

Figure 1 is a front elevation of my device;

Fig. 2 is section taken substantially on the line 2--2 of Fig. 1; and

Fig. 3 is a section taken substantially on line 3--3 of Fig. 1.

Referring to the drawings, wherein I have illustrated the preferred embodiment of my invention, there are shown a pair of standards, uprights or frame members 1, each having a bored boss 2 thereon to rotatably receive the ends 4 of a forming or shaping roll 3. A set screw 5, or other suitable or equivalent means, is threaded into one of the bosses 2, as shown in the drawings, to engage one of the ends 4 of 45 the roll 3 and hold it against rotation whenever desired. One or more brace rods 6 and 7 may be secured between the standards 1 to hold them in place and prevent any accidental displacement of the parts.

A plate or rod 8 is adapted to be arranged longitudinally of the roll 3 and to be ad-

justably clamped on said roll by means of a series of spaced screws 9, each preferably having a washer 10 between its head and the plate. Any suitable printing plate, 60 electrotype or the like may be shaped about the roll 3 and in the embodiment shown, there is represented a printing plate 11, having any sort of imprint design 12 thereon. The plate is adapted to be arranged on said roll with one edge 13 clamped between the rod 8 and the roll, as shown more clearly in the drawings. It will be noted that the edge of the rod 8 forms a straight-edge 70 whereby the printing plate may be aligned 70 as desired.

Any suitable means for pressing the plate about the roll may be employed, but I have found it satisfactory to use a hand tool having a handle portion 14 and a head portion 15 at one end thereof to cooperate with the roll to bend, "set" or shape the printing plate 11 thereabout. The head portion 15 of the tool forms a T with the handle portion 14, and the end of the head portion is tapered or beveled, as at 16, so as to form a very narrow edge or face to bear upon or engage the printing plate without danger of marring the raised printing design thereof. Where the printing plate 11 has any sort of imprint thereon, it is possible to have the striking face of the tool engage said plate between the lines of the imprint, as the tool has a very narrow face. In some cases, for example where a half tone plate 80 is to be formed a block of wood or the equivalent may be placed on the face while forming.

An aperture 17 may be provided at any suitable point in the handle for the purpose 95 of hanging up said tool when desired, and for the additional purpose of engaging the pins with which the set screws 5 and 9 are provided to tighten or release said screws.

In operation, one edge of the plate is 100 adjustably clamped between the plate 8 and roll 3, and with a mallet or any other suitable tool, the face 16 of the T-head tool is caused to be pressed upon the plate 11 to shape it about said roll. In order that the portion of the plate 11 that is to be bent about the roll may always be at the most convenient or advantageous portion of the roll, the set screw 5 may be released so that the roll may be partially rotated to bring the 105 plate to the desired position to be worked upon, until it is desired to release it again 110

to move the roll farther. It will be apparent that the front side of the device, which is toward the free edge of the plate 11, is clear of obstruction, as the brace rods 5 6 and 7 are placed upon the rear portion of the standards. This makes it very easy to align the plate and perform the bending operation without hindrance. When a plate is formed or "set" upon the shaping roll 10 3, it will conform exactly to the periphery of said roll and as said periphery is exactly like that of the printing roll or other holding means in the printing press upon which the plate 11 is to be secured for printing, 15 the under surface of the plate will conform precisely to the body contour of said last-mentioned means.

Having thus described my invention, it is obvious that various immaterial modifications may be made in the same without departing from the spirit of my invention; hence I do not wish to be understood as limiting myself to the exact form, construction, arrangement and combination of parts 25 herein shown and described, or uses mentioned.

What I claim as new and desire to secure by Letters Patent is:

1. In a device of the kind described and in combination, a roll, means for rotatably mounting said roll, means for adjustably locking said roll at any point of its rotation, and means for shaping a printing plate about said roll to conform to the peripheral 35 surface of said roll.

2. In a device of the kind described and in

combination, a frame, a roll journaled therein, means for locking said roll at any point of its rotation, a bar arranged longitudinally of said roll, adjusting screws for 40 clamping the edge of a printing plate between said bar and roll, and means for pressing said plate on said roll so that it may be shaped to conform to the peripheral surface of said roll. 45

3. In a device of the kind described and in combination, a shaping roll having a peripheral surface conforming to that of the plate-holding roll of a printing mechanism, a frame for rotatably carrying said roll, 50 means for locking said roll in said frame at any point of its rotation, and means for holding a printing plate on said roll for shaping it thereabout.

4. In a device of the kind described and in combination, a shaping roll having a peripheral surface conforming to that of the plate-holding roll of a printing mechanism, a frame having bored bosses for rotatably carrying said roll, means for locking said 60 roll in said bosses of said frame at any point of rotation, and means for adjustably clamping a printing plate on said roll along one edge for shaping said plate about said roll. 65

In testimony whereof, I have hereunto signed my name in the presence of two subscribing witnesses.

CLAUDE L. POST.
